UNITED STATES PATENT OFFICE.

JOHN W. WILLIAMS, OF COZAD, NEBRASKA.

FEEDING DEVICE.

1,208,067.

Specification of Letters Patent. Patented Dec. 12, 1916.

Application filed April 1, 1916. Serial No. 88,353.

To all whom it may concern:

Be it known that I, JOHN W. WILLIAMS, a citizen of the United States, residing at Cozad, in the county of Dawson and State 5 of Nebraska, have invented certain new and useful Improvements in Feeding Devices, of which the following is a specification, reference being had to the accompanying drawings.

65

10 This invention relates to certain improvements in feeding devices and has relation more particularly to a device of this general character especially designed and adapted for use in connection with threshing 15 chines or the like; and it is an object of the invention to provide a novel and improved feeding device of this general character whereby grain may be delivered to the threshing machine with greater facility and 20 convenience.

Furthermore it is an object of the invention to provide a novel and improved device including a main feeding member with which coact one or more laterally directed 25 wings adapted to be driven in unison with the main feeding member and whereby said wing or wings may be readily and conveniently adjusted into or out of operative position in accordance with the requirements 30 of practice.

The invention consists in the details of construction and in the combination and arrangement of the several parts of my improved feeding device whereby certain important advantages are attained and the device is rendered simpler, less expensive and otherwise more convenient and advantageous for use, all as will be hereinafter 35 more fully set forth.

40 The novel features of the invention will hereinafter be definitely claimed.

In order that my invention may be the better understood, I will now proceed to describe the same with reference to the accompanying drawings, wherein—

45 Figure 1 is a view in top plan illustrating an embodiment of my invention; Fig. 2 is a sectional view taken substantially on the line 2—2 of Fig. 1; Fig. 3 is a sectional view taken substantially on the line 3—3 of Fig. 50 1; and Fig. 4 is a sectional view taken substantially on the line 4—4 of Fig. 3.

55 As disclosed in the accompanying drawings, F denotes a main feeding member of a character generally employed in connection with threshing machines or the like and

herein disclosed as comprising the side boards 1 between which is mounted the table 2. Passing over the table 2 is the upper stretch of the endless member E 60 herein disclosed as comprising side belts 3 tied or connected by the cross bars or slats 4 and which coact with the table 2 in a manner and for a purpose which is believed to be self-evident.

65

The side belts 3 as herein disclosed are directed around the pulleys 5 suitably affixed to the shaft 6 rotatably supported by the side boards 1 and extending beyond opposite sides thereof, one end portion of the 70 shaft 6 being adapted to be coupled, as indicated at 7, with a suitable source of power. Each of the side boards 1 at the outer end thereof is provided with the upstanding posts 8 which afford a mounting for the 75 shaft 9 disposed longitudinally of the side board 1 and with which is pivotally engaged the side boards 10 of a laterally adjustable wing W, the outward movement of said wing W being determined by the stop 80 11 carried by the side board 1 and with which a side board or member 10 is adapted to contact, as is thought to be clearly shown in the accompanying drawings.

The outer or free extremities of the side 85 boards or members 10 are tied or connected by the non-rotative shaft 12 upon which is rotatably mounted the pulleys 14 and around which are directed the side belts 15 which are also directed around the pulleys 90 16 fixed to the shaft 9 hereinbefore referred to. The belts 15 are tied or connected by the cross slats or bars 17 which are adapted to travel above the table or platform 18 interposed between and secured to the side 95 boards or members 10 of the wing W and overlying the shafts 12 as is clearly illustrated in Fig. 4 of the accompanying drawings.

Disposed vertically of the side board 1 adjacent the outer end thereof is the rotating shaft 19 having its upper extremity operatively engaged with the shaft 9, as is indicated at 20, and its lower extremity operatively engaged, as at 21, with the shaft 6 100 hereinbefore referred to, and it is to be observed that the connections 20 and 21 are such as to cause the upper stretches of the belts 15 to move inwardly when the feeder is in operation so that the grain or the like 105 deposited upon the table or platform 18 will be discharged upon the table or platform 2

of the main feeding member F, hereinbefore referred to.

It is to be understood that the grain is adapted to be thrown upon the belts 15 manually through the use of forks as is now generally done. The wings W when swung outwardly are adapted to assume and maintain substantially a horizontal position and it is to be observed that the stops 10 11 are so positioned as to prevent movement of the wings W beyond the plane substantially at right angles to the side boards 1.

By having the side boards or members 10 15 pivotally engaged with the shaft 9, it will be perceived that the wing W may be readily swung inwardly relative to the feeding member F when the device is not in use and as the requirements of practice may require.

20 From the foregoing description, it is thought to be obvious that a feeding device constructed in accordance with my invention is of an extremely simple and comparatively inexpensive nature and is particularly well adapted for use by reason of the convenience and facility with which it may be assembled, and it will also be obvious that my invention is susceptible of some change and modification without material departure from the principles and spirit thereof 25 and for this reason I do not wish to be understood as limiting myself to the precise arrangement and formation of the several 30

parts herein shown in carrying out my invention in practice.

35

I claim:

The combination with a feeding member including side boards, an endless conveyer movable between said side boards, and a driving shaft for said conveyer; of posts 40 secured to each of the side boards and extending thereabove, shafts rotatably supported by the extended portions of the posts and operatively engaged with the drive shaft of the endless conveyer, a laterally disposed wing pivotally engaged with each of said last named shafts, each of said wings including an endless conveyer movable toward the feeding member and operatively engaged with the shaft of the adjacent side 50 board of the feeding member, and outwardly disposed stops carried by the sides of the feeding member and coacting with the wings for preventing the outward movement of the wings extending beyond substantially the horizontal, said wings when in substantially a horizontal position occupying a horizontal plane above the horizontal plane of the side boards of the feeding member. 55 60

In testimony whereof I hereunto affix my signature in the presence of two witnesses.

JOHN W. WILLIAMS.

Witnesses:

U. HARRISON,
PEARL LANHAM.
